UNITED STATES PATENT OFFICE

AUGUST J. MOTTLAU, OF PITTSBURGH, PENNSYLVANIA, ASSIGNOR TO WESTINGHOUSE ELECTRIC & MANUFACTURING COMPANY, A CORPORATION OF PENNSYLVANIA

THERMAL RELAY

Application filed January 14, 1927, Serial No. 181,663.

My invention relates to relays and particularly to thermal relays.

An object of my invention is to provide a thermal relay that may be so adjusted as to be operable to maintain a wide range of average temperatures.

Another object of my invention is to provide a thermostatically actuated simple lever or movement-multiplying mechanism for operating an electric switch; and

Another object of my invention is to provide a thermal relay that shall have a switch capable of interrupting or closing an electric circuit instantaneously.

In practicing my invention, I provide a switch, a movement-multiplying mechanism for actuating the switch, and a thermo-responsive means for actuating and controlling the movement-multiplying mechanism. The switch which I propose to use in the embodiment of my invention is one that is capable of making and breaking electric circuits at a relatively high rate of speed. The switch is of the type that is normally in a circuit-closing position. Thus, it will return to the circuit-closing position automatically upon the release of a force that actuates it to a circuit-opening position.

The movement-multiplying mechanism comprises a floating lever having a fulcrum and pivot so located with respect to the ends thereof that a long lever arm and a relatively short force arm are provided. In a preferred form of my invention, the lever is supported either by a thermostatically actuated means or by a thermo-responsive means and the switch.

The distance between the fulcrum and the lever may be varied by adjusting means in accordance with an average condition or temperature to be maintained by the thermal relay. Means are provided also by which the length of the force arm may be varied in accordance with any temperature differential desired to which the relay is operable.

When controlling temperatures encountered in refrigerators are to be regulated, I prefer that the fulcrum be stationary and the pivot movable relatively thereto; but if temperatures of electrically heated ovens, fur-

naces, and similar devices are to be regulated, it is preferable that the fulcrum be movable relatively to the pivot.

The movement-multiplying mechanism is applicable to be controlled or actuated by many different means, such as thermo-responsive, pressure responsive, or other similar devices.

The operation of the relay is substantially as follows:

When the thermo-responsive means has attained a predetermined temperature, a pressure is applied to the force arm of the lever, causing it to rock on its fulcrum, thereby actuating the lever arm into engagement with the switch. When the lever has rocked on its fulcrum through a certain angular space, the switch is actuated to its circuit-opening position. Upon the cooling of the thermo-responsive means, the lever is rocked in the opposite direction on the fulcrum by spring means or by the self-resetting switch, thereby actuating the switch to its circuit-closing position. When the thermo-responsive means again attains the above predetermined temperature, the aforesaid operation is repeated.

In the drawings, Fig. 1 is a top plan view, partially in section, of the device embodying my invention.

Fig. 2 is a view, in front elevation, of the device illustrated in Fig. 1.

Fig. 3 is a view, in front elevation, of the device illustrated in Fig. 2 part of the cover being removed therefrom.

Fig. 4 is a top plan view of a detail embodied in the fulcrum end of the lever arm of the device illustrated in Figs. 1 to 3, inclusive.

Fig. 5 is an end view of the device illustrated in Fig. 4.

lay 11 comprises a thermo-responsive means 12, a movement-multiplying mechanism 13 and a circuit-controlling switch 14.

One form of the thermo-responsive means

12 comprises an elongated tubular member 15 having a relatively high temperature coefficient of expansion and a rod 16 extending therethrough, having a relatively low temperature coefficient of expansion.

10 One end of the rod 16 is provided with a screw-threaded end portion 17 having a smaller diameter than that portion which extends through the tubular member.

15 A push rod 18 is suitably secured to the other end of the rod 16. A pivot-supporting member 19 of substantially L-shape is secured to the free end of the push rod 18 by a pin 20.

20 The tubular member 15 is provided with external screw-threads at one end 21 and internal screw-threads at the other end 22. A plug 23, having screw-threaded engagement with the end 22, is provided with a hole 24 through which the portion 17 of 25 the rod 16 projects. The rod 16 is secured to the plug 23 by means of nuts 25.

25 The tubular member 15 may be of any length, depending upon the required sensitivity of the relay to temperature changes.

30 The rod 16 and the push rod 18 may be of such low-expansion material as invar.

35 The movement-multiplying mechanism 13 comprises a fulcrum wedge 26, a lever-arm shoe 27 and an elongated floating lever 28. The shoe 27 is secured to one end of the lever 28 by such means as pins 31.

40 One end of the lever 28 is provided with a projection or knob 32 that engages one end of the circuit-controlling switch 14, and the shoe 27 engages a pivot screw 33.

45 The pivot screw 33 has screw-threaded engagement with the pivot-supporting member 19. One end of the screw is provided with a circular head having a knife edge 34 thereon that directly engages the shoe 27.

50 The lever-arm shoe 27 is illustrated in detail in Figs. 4 and 5 of the drawings. As here shown, the shoe 27 is provided with a tapered end portion that extends into a slot 55 in the lever 28 in which position it is held by the pins 31. The other end of the shoe is slotted longitudinally along opposite edges. A portion 35 between the slots is bent slightly in one direction (see Fig. 5) and edge portions 36 are bent slightly in the opposite direction so that the bottom faces of portions 36 are located substantially in the plane of the top face of the portion 35.

60 The fulcrum wedge 26 is illustrated in detail in Fig. 6 and comprises an elongated portion 37 having holes 38 adjacent to the ends thereof, and a pair of laterally-extending knife-edges 39. The knife-edges 39 are so spaced that they rest upon the bot-

tom face of the portions 36 of the shoe 27. It is to be noted that the knife-edges 39 and 34 engage the shoe 27 in substantially the same plane.

65 The switch 14, the movement-multiplying mechanism 13 and the push rod 18 are enclosed in a casing 41 comprising a base 42 and a cover 43.

70 The base 42 is substantially rectangular in lateral and in longitudinal section, with the exception of an end portion 44 that is substantially circular. The top edges of the walls of the base 42 are rabbeted (see Fig. 1) for a purpose to be hereinafter set forth. A flange 45 extends laterally of the 75 circular end portion 44 and is integral with the base 42. A boss 46 on the flange 45 is provided with a hole 47, through which the push rod 18 may move freely, and internal screw threads by means of which the 80 tubular member 15 may be secured to the base 42.

85 The base 42 is provided with a rectangular opening 48 and a circular opening 49 for purposes to be hereinafter set forth.

90 The cover 43 conforms, in contour, to the base 42 and is provided with complementary rabbeted edges on its walls that cooperate to form a rabbet joint with the base.

95 A hole 51 is located in a circular end portion 52 of the cover 43, complementary to the portion 44, across which extends a bridging member 53. Tapped holes 54 and 55 (see Fig. 7) are located in the bridging member 53. Pins 56 project through and beyond the member 53 and are so spaced between the holes 54 and 55 that they register with the holes 38 in the fulcrum wedge 26 and serve as guides along which the fulcrum may move.

100 A fulcrum-adjusting screw 57 having screw-threaded engagement with the hole 54, limits the movement of the fulcrum wedge 26 along the pins 56. A knob 58, to which a pointer 59 is attached, is suitably secured 105 to the screw 57 by means of which movement of the wedge 26 may be limited, whereby the relay may be so adjusted that it responds to any average condition or temperature desired. The hole 51 in the cover 43 is provided with a cover 61 that is secured to the bridging member 53 by means of screws fitting into the holes 55.

110 An insulating bushing 62 projects through the cover 43 and is suitably secured thereto. A reset and guide member 63 projects through the bushing 62 with which it has screw-threaded engagement, into the casing and through an aperture 64 in the lever 28. The member 63 restrains the lever 28 from lateral and longitudinal movement but permits it to move therealong.

115 The cover 43 is secured to the base 42 by means of bolts that have screw-threaded engagement with lugs 65 and 66 in the base 42.

The base 42 and the cover 43 are provided with semi-circular openings located in the circular end portions that cooperate to form an opening 67 through which the pivot screw 33 extends and in which it may be free to move in the direction of movement of the push rod 18.

The casing 41 should be made by die-casting such material as aluminum or of moulded non-conducting material, such as bakelite, although I do not wish to be limited to this particular metal or material or to this method of making the same.

The switch 14 (see Figs. 1 and 3) comprises a resilient metallic frame 68 having a pair of spaced elongated apertures 69 adjacent to the long edges thereof. The middle portion of the sides of the frame are so formed that a section 71 of substantially W-shape is provided.

A portion 72, between the apertures 69, is bent laterally of the frame 68 at the ends thereof, substantially as indicated by the curved end portions 73, thus causing the portion 72 to be confined in an arched position (see Fig. 1). A contact member 74 is secured to the portion 72 by any suitable means.

The frame 68 is secured to a switch base 75, of insulating material, by screws 76 that extend through the portion 71 of W-shape and the base 75. The base 75 is provided with a relatively narrow rectangular portion 77 that fits into the rectangular opening 48 and is secured in this position by means of a contact screw 78 that extends through the switch base 75, a washer 79 and a pair of nuts 81. The contact screw 78 is provided with a suitable head 82 that constitutes a cooperating contact for the contact 74. The contact screw 78 constitutes one terminal of the switch 14, and one of the screws 76 constitutes its other terminal.

An adjusting screw 83 extends through one end of the frame 68 and the bushing 49, by means of which that end of the frame may be bent downwardly towards the switch base 75 to any desired extent and be fixed in this position by means of a lock nut. The other end of the frame 68 normally engages the knob 32 of the lever 28.

The contacts 74 and 82, as illustrated in Fig. 1 of the drawings, are normally in a circuit-closing position, but, upon bending a that end of the frame 68, which engages the knob 32 in a direction towards the switch base 75, the portion 72 of the frame is caused to pass through a state of unstable equilibrium from which it moves, with a snap action, to disengage the contacts 74 and 82. When that end of the frame 68 is released, the portion 72 again passes through the state of unstable equilibrium and engages the contact 74 with the contact 82 as illustrated in Fig. 1.

With the relative positions of the pivot screw 33 and the fulcrum wedge 26 as illustrated in Figs. 1 and 3 of the drawings, the thermal relay is adapted for controlling the temperatures usually encountered in refrigerators. As shown in Fig. 1, the relay 11 may be assumed to be secured to a wall of a refrigerator and the tubular member 15 to extend into the refrigerator chamber through a hole in the wall. The relay 11 is positively secured to the wall by means of bolts 84 that pass through holes 85 in the flange 45.

When the temperature within the refrigerator attains a predetermined low value, the tubular member 15 contracts to cause the rods 16 and 18 to so move the knife edge 34 of the pivot screw 33 against the lever shoe 27 that the lever shoe engages the knife edges 39 of the fulcrum wedge 26. Upon further contraction of the tubular member 15, the lever 28 is caused to rock on the knife edges 39 until the knob 32 has so bent the frame 68, as previously set forth, that the contact 74 has been disengaged from the contact 82.

It is to be assumed that, upon the disengagement of the contacts 74 and 82, an electric motor or other electric translating device used to drive an artificial refrigerating machine is deenergized, thereby preventing further cooling of the chamber in which the tubular member 15 may be located.

As the temperature of the tubular member 15 increases, it expands, thereby moving the push rods 16 and 18 outwardly; therefore, the lever arm shoe 27 tends to move away from the fulcrum wedge 26 but, because of the resiliency of the frame 68, the shoe 27 is held in rocking engagement with the knife edges 39 until the switch and lever assume the positions substantially as illustrated in Fig. 1, in which position the contact 74 engages contact 82. The energizing circuit of an electric motor or other device controlled by the switch 14 being thus reestablished, the refrigerating apparatus is again set into operation.

While the average temperature or condition to be controlled is determined by the relative position of the fulcrum wedge 26 with respect to the lever arm shoe 27, the maximum and minimum values of the temperature or condition are regulated by means of the pivot screw 33, as such values are necessarily a function of the length of the force arm, or the distance between the knife edges 34 and 39.

If the force arm is relatively long, the difference between the maximum and minimum conditions, with respect to an average condition, will be proportional to its length. The difference between the maximum and minimum conditions is termed a differential, and when specifically relating to temperatures, the difference is known as a temperature

differential. By the term temperature differential, as applied to the invention herein described, is meant the difference between the temperature at which the contacts 74 and 82 are actuated to a disengaged position and that at which they are reengaged. To increase the temperature differential, the distance between the knife edges 34 and 39 is increased, whereas, to decrease the differential, the distance is shortened.

If an average temperature of substantially 50° F. is to be maintained, the fulcrum wedge 26 may, by way of illustration, be assumed to be in the position substantially as illustrated in Fig. 1. If, however, the average temperature to be maintained is 40° F., the knob 58 is turned in a counter clockwise direction, as indicated in Fig. 2, until the pointer 59 coincides with the 40° mark on the cover 61. Upon a sufficient cooling of the tubular member 15, the lever shoe 27 is moved into engagement with the knife edges 39, which movement continues until the portion 37 of the fulcrum wedge 26 engages the screw 57. A further contraction of the tubular member 15 will rock the lever 28 on the knife edges 39 until the knob 32 so bends the frame 68, that the contacts 74 and 82 become disengaged.

It is obvious that the tubular member 15 must contract or shorten considerably more to actuate the switch 14 in order to maintain a temperature of 40° than a temperature of 50°, because the movable fulcrum 26 is positioned at a relatively greater distance away from the lever shoe 27.

If the relay 11 is to maintain a temperature higher than 50° F., the knob 58 is turned in a clockwise direction, thereby moving the fulcrum wedge 26 towards the knife edge 34 of the pivot screw 33.

The sensitivity of the relay 11 is greatly affected by the length of the tubular member 15, for the greater its length, the greater will be its increase in length per degree change in temperature.

The arrangement of the pivot screw 33, the fulcrum wedge 26, and the lever 28, as illustrated in Figs. 1 and 3 is adapted for controlling temperatures encountered in refrigerators and the like, but, in order to control temperatures common to electric ovens, furnaces and the like, I prefer that the arrangement shall be according to that shown in Figs. 8 and 9.

In Figs. 8 and 9, the pivot screw 33, being secured to the casing 41, is stationary relatively to the fulcrum wedge 26, and the adjusting screw 57 which are carried by a frame 87.

The frame 87 is suitably attached to a push rod 88, similar to the rod 18 (see Fig. 1). A pair of guide pins 86, secured to the frame 87, register with the holes 38 in the wedge 26, whereby the wedge may slide therealong.

The screw 57, having screw thread engagement with the frame, may be adjusted to limit the movement of the wedge 26 on the pins 86.

When the tubular member 15 expands, the push rod 88 is moved outwardly, thus actuating the knife edges 39 into engagement with the lever-shoe 27, thereby causing the lever 28 to pivot on the knife edge 34. It is to be understood that push rods 18 and 88 may be actuated by pressure derived from sources other than thermal means. A sufficient expansion of the tubular member 15 will actuate the switch 14 substantially as previously set forth herein.

By means of the screw 57 and the pivot screw 33, the relay 11, having modifications shown in Figs. 8 and 9, may be adjusted to maintain any desired average temperature and to operate with any temperature differential, substantially as hereinbefore set forth.

By experiment, I have found that the switch contacts 74 and 82 may be disengaged upon a contraction of the tubular member 15 equal to approximately .0015 inches. By choosing a tubular member of the proper length, and by suitably adjusting the length of the force arm, a contraction equal to the above value may be obtained by a temperature change of 1° F.

By my invention, I have provided a thermal relay having one adjustment for regulating its temperature differential, whereby a predetermined average temperature may be maintained, and another adjustment for causing the relay to be operative to maintain any desired average temperature.

Various modifications may be made in the device embodying my invention without departing from the spirit and scope thereof. I desire, therefore, that only such limitations shall be placed thereon as are imposed by the prior art and the appended claims.

I claim as my invention:

1. The combination with a circuit-controlling device, a thermo-responsive means having a knife edge at one end thereof, a knife-edge-pivot means, and a lever operatively connecting the circuit-controlling device and the thermo-responsive means and having opposite faces at one end thereof lying in one longitudinal plane and operatively engaging the respective knife edges.

2. The combination with a circuit-controlling device, a thermo-responsive means having a knife edge at one end thereof, a knife-edge-pivot means, and a lever operatively connecting the circuit-controlling device and the thermo-responsive means and having separated end portions at one end thereof bent respectively in opposite lateral directions to cause the respective knife edges to engage the lever in substantially the same longitudinal plane.

3. The combination with a circuit-controlling device, an expansion and contraction member having a knife edge at one end thereof, an adjustable knife-edge-pivot means located relatively close to the first knife edge, and a lever extending between the circuit-controlling device and the expansion and contraction member, said lever having longitudinally-extending tongues alternately oppositely bent laterally of the lever, whereby the opposite surfaces of the tongues operatively engaging the respective knife edges lie in substantially the same plane longitudinally of the lever.

10 15 In testimony whereof, I have hereunto subscribed my name this 3rd day of January, 1927.

AUGUST J. MOTTLAU.
